UNITED STATES PATENT OFFICE

DAVID E. ROSS, OF LA FAYETTE, INDIANA

CAM AND LEVER STEERING GEAR

Application filed October 15, 1928. Serial No. 312,616.

This invention is an improvement in cam and lever steering gears of the general type shown in my Patent No. 1,567,997 dated December 29th, 1925. In this type of cam and lever steering gear the actuating member is provided with a helical groove which is engaged by a pin on the arm of the rocker shaft.

The object of the present invention is to provide a construction in which the actuating member is provided with a helical rib or rail and the rocker arm is provided with a self adjusting grooved member adapted to engage the rib, the parts so cooperating that the actuating member will in effect move the rocker arm practically in the same way that it is moved in my aforesaid patented construction.

In the accompanying drawings I have illustrated the at present preferred form of the invention and two modifications thereof for the purpose of illustrating but not exhausting the capabilities of embodiment of the invention. I will explain the invention with reference to said drawings to enable others to adopt and use the same, and refer to the claims following the description for summaries of the essentials of the invention and novel features of construction and novel combinations of parts for which protection is desired.

In said drawings;

Fig. 1 is a sectional view partly in section of the lower part of a cam and lever steering gear equipped with my invention.

Fig. 2 is an enlarged detail transverse section on the line 2—2 Fig. 1.

Fig. 3 is a detail section on the line 3—3 Fig. 2.

Fig. 4 is a detail face view of the grooved member applied to the rocker arm.

Figs. 5, 6 and 7 are views similar to Figs. 2, 3 and 4 respectively showing a slight modification of the invention.

Figs. 8, 9 and 10 are views similar to Figs. 2, 3 and 4 respectively, illustrating another modification of the invention.

The actuating member 1 is preferably cylindrical and adapted to be attached to the steering shaft S of a steering gear in any suitable manner, as in my aforesaid patent.

This actuating member is provided with a helical rib or rail 1a which may be given any desired pitch. This helical rib may be either uniform in pitch or its pitch may vary from the center toward each end thereof, as is the groove in my aforesaid patent.

In cross section this rib is much like a pinion tooth in form and is adapted to be engaged by a self adjusting grooved member whose groove corresponds in cross section to the cross section of the rib. At present I prefer to employ a spherical member 2 (see Figs. 1—4), having an annular circumferential groove 2a which engages the rib 1a as shown in Fig. 2. This member 2 is confined within a recess 3b in the end of the arm 3a of a rocker shaft 3 such as described in my aforesaid patent, and the member is seated in a hardened steel bearing member 2c placed in the outer end of said recess—the outer end of this bearing member 2c abutting against the wall of the casing, or against an adjusting plate P which is usually interposed between the arm and wall of the casing C to keep the member on the arm properly engaged with the actuating member.

The spherical member 2c may be made of bronze or other suitable metal. The helical rail or rib 1a on the actuating member 1 can be varied in pitch if desired like the groove in the actuating member of my patented cam and lever gear; and the groove 2a in the spherical member closely engages the rib 1a and has a rolling contact therewith and can readily adjust itself to any variation in pitch of the rib.

The rib 1a and the groove 2a are cut to closely engage and fit each other like the teeth of intermeshing gears and as the actuating member is rotated the rib engaging the spherical member forces the rocker arm to move longitudinally of the actuating member and turn the rocker shaft. The rib and groove are so cut that continuous contact is always maintained between them and in the actual gear the grooved spherical member will at all times assume the proper true position relative to the rib no matter what its pitch may be.

In the construction shown in Figs. 4, 5 and

6 the actuating member 1 is as shown in Figs. 1-4 but instead of using a spherical grooved member 2 a roller or wheel 2 α is employed. This roller has a peripheral groove 2 α x similar to the groove in member 2 and adopted to engage the rib 1a above described. The roller 2 α is shown as mounted in a slot 4b in a cylindric member 4, the pulley 2 α being rotatably mounted on a pin 4a which transfixes the 10 cylindric member. The outer end of the cylindric member 4 abuts against the adjusting plate P or the wall of the casing in the same manner as the bearing member 2c above described. The roller 2 α projects sufficiently 15 beyond the end of the cylindric member 4 to properly engage the rib 1a as shown in Figs. 5 and 6.

In the construction shown in Figs. 5, 6 and 7 the roller has the same capacity for universal self-adjustment relative to the actuating member as the spherical member 2 shown in Figs. 1 to 4. When a sphere is used, slight flat annular cuts may be made at the outer edges of the grooves as indicated at 2s to prevent any wedging between the rib and walls of the groove in transmitting. If the ball or sphere 2 is used, it is self-evident that due to its sphericity it will turn and follow the helical angularity of the cam. The roller shown 25 in Figs. 5 to 7 has the same universal self-adjusting effect as the cylindric member supporting it will turn within the opening in the arm and allow the roller to follow the helical angularities of the rib. Both sphere and 30 roller produce a rolling action instead of a frictional slippage as in my aforesaid patented cam and lever steering gear.

In the construction shown in Figs. 8, 9 and 10 cylindric member 5 is rotatably mounted 40 within the arm 3a and has a groove 5a in its inner end which directly engages the rib 1a on the actuating member. The outer end of member 5 abuts against the adjusting plate P or casing 4, as in Fig. 1. This cylindric member 5 can obviously adjust itself to the variations in pitch of the rib 1. In this construction the grooved end of the pin embraces the rib and transmits motion in either direction, but with more friction than with 45 the ground sphere or roller. The groove in the cylindric member 5 must not tightly fit the rib throughout its length, but must be a composite of the various pitches of the rib; which will be varied according to the desired 50 conditions for any make of car; the sphere 2 or the pulley 2 α have theoretically a line contact; such variations need not be taken into account.

In the patented cam and lever steering gear, 55 during the heat treatment the actuating member has a tendency to contract the groove in some places and widen it in others; and the grinding has been most difficult. In my present invention the helical rib projects from 60 the cylinder and can be easily cut by a strad-

dling mill, and the rib can be ground by abrasive wheels of the same cross-section as the straddle mill. The rib on the cylinder is in effect as a helix around the cylinder, with a variable helix angle to suit any desired 70 working conditions and the self-adjusting grooved contact member engaging said rib will transmit motion, and always maintain itself at the proper angle to the rib.

I claim:

1. In a steering gear; a rotatable actuating member provided with a projecting helical rib, a rocker arm beside the actuating member, and a member having a groove engaging said rib and pivotally mounted on the rocker arm so that it can automatically adjust itself relative to the arm and the actuating member and maintain accurate engagement with the rib in all operative positions of the rocker arm. 75

2. In a steering gear; a rotatable actuating member having a projecting helical rib, a rocker arm beside the actuating member, and a member having a groove engaging said rib and pivotally mounted on the arm so that it can rotate on an axis perpendicular to the axis of the actuating member, whereby said member can automatically adjust itself relative to the arm and the actuating member and maintain accurate engagement with the rib 80 in all operative positions of the rocker arm. 85

3. In a steering gear; a cylindric actuating member having a projecting helical rib on its periphery, means for rotating said actuating member, a rocker arm beside the actuating member, and a member mounted on the arm and having a groove engaging said rib and capable of rotation on an axis perpendicular to the axis of the actuating member whereby said member can automatically adjust itself relative to the arm and the actuating member and maintain accurate engagement with the rib in all operative positions of the rocker arm. 100

4. In a steering gear; a rotatable actuating member having a projecting helical rib, a rocker arm beside the actuating member, and a member rotatably mounted on the rocker arm and having a peripheral groove engaging the said rib; said member being rotatable on its own axis and also rotatable on the arm on an axis perpendicular to the axis of the actuating member, whereby said member can automatically adjust itself relative to the arm and the actuating member and maintain accurate engagement with the rib in all operative positions of the rocker arm. 110

5. In a steering gear; a cylindric actuating member having a projecting helical rib on its periphery; means for rotating said actuating member, a rocker arm beside the actuating member, and a member rotatably mounted on the rocker arm and having a peripheral groove engaging the said rib; said member being rotatable on its own axis and 120

- also rotatable on the arm on an axis perpendicular to the axis of the actuating member, whereby said member can automatically adjust itself relative to the arm and the actuating member and maintain accurate engagement with the rib in all operative positions of the rocker arm.
6. In a steering gear; a rotatable actuating member having a projecting helical rib, a rocker arm beside the actuating member, and a spherical member rotatably mounted on the arm and having a circumferential groove engaging the rib, whereby said member can automatically adjust itself relative to the arm and the actuating member and maintain accurate engagement with the rib in all operative positions of the rocker arm.
7. In a steering gear; a rotatable actuating member having a projecting helical rib on its periphery, a rocker arm beside the actuating member; and a spherical member rotatably mounted on the arm and capable of rotation on an axis perpendicular to the axis of the actuating member; said spherical member having a circumferential groove adapted to engage the rib whereby said member can automatically adjust itself relative to the arm and the actuating member and maintain accurate engagement with the rib in all operative positions of the rocker arm.
8. In a steering gear; a cylindric actuating member having a projecting helical rib on its periphery, means for rotating said actuating member, a rocker arm beside the actuating member, and a spherical member rotatably mounted on the arm and capable of rotation on an axis perpendicular to the axis of the actuating member, said spherical member having a circumferential groove engaging the rib, whereby said member can automatically adjust itself relative to the arm and the actuating member and maintain accurate engagement with the rib in all operative positions of the rocker arm.
9. In a steering gear; a cylindric rotatable actuating member provided with a projecting helical rib on its periphery; a rocker arm pivotally mounted beside the actuating member; a stub shaft mounted on the rocker arm and rotatable on an axis perpendicular to the axis of the pivot of the rocker arm; and a roller having a peripheral groove rotatably mounted on said stub shaft and engaging the said rib; said roller being rotatable on an axis perpendicular to the axis of the stub shaft whereby said roller can automatically adjust itself relative to the arm and the actuating member and maintain accurate engagement with the rib in all operative positions of the rocker arm.
10. In a steering gear; a cylindric actuating member having a projecting helical rib on its periphery; means for rotating said actuating member; a rocker arm beside the actuating member swinging on an axis perpendicu-
- lar to the axis of the actuating member and having a socket in its end adjacent the actuating member; and a cylindric member rotatably mounted in said socket, and having a transverse groove in its outer end engaging the said rib whereby said member can automatically adjust itself relative to the arm and the actuating member and maintain accurate engagement with the rib in all operative positions of the rocker arm.
- DAVID EDWARD ROSS.
